GEORGE L. BAXTER, Inventor

By E. C. Brown

Attorney.

UNITED STATES PATENT OFFICE.

GEORGE L. BAXTER, OF SALT LAKE CITY, UTAH.

FOLDING IRONING-BOARD.

976,621.

Specification of Letters Patent. Patented Nov. 22, 1910.

Application filed June 20, 1910. Serial No. 567,971.

To all whom it may concern:

Be it known that I, GEORGE L. BAXTER, a citizen of the United States of America, residing at 1338 Bryan avenue, Salt Lake City, in the county of Salt Lake and State of Utah, have invented certain new and useful Improvements in Folding Ironing-Boards, of which the following is a specification, reference being had therein to the accompanying drawing.

This invention relates to ironing tables and the principal object of the same is to provide novel means whereby the table may be supported from a wall of a room in a manner that permits the same to be readily swung to a position for use or swung in position parallel to the wall so that it will occupy a small amount of space when not in use.

20 In carrying out the objects of the invention generally stated above it will be understood, of course, that the essential features thereof are necessarily susceptible of changes in details and structural arrangements, one 25 preferred and practical embodiment of which is shown in the accompanying drawings, wherein:—Figure 1 is a perspective view of the ironing table as it appears when ready for use. Fig. 2 is a side view showing 30 the folded position of the board. Fig. 3 is a detail fragmentary perspective view of the support for the board. Fig. 4 is a view in front elevation showing the board folded. Fig. 5 is a fragmentary sectional view showing 35 the manner of supporting the board when in use. Fig. 6 is a plan view of a hinge blank used in connection with this invention. Fig. 7 is a detail perspective view of the hinge formed from said blank.

40 Referring to said accompanying drawings by numerals, it will be seen that the improved ironing table comprises a wall engaging frame that is formed of the spaced parallel vertical side members 1—1^a that are 45 suitably attached to studding A or other portions of a wall. Said side members have their upper end portions connected by the horizontal bar 2 and their lower end connected by a similar bar 3. Side member 1 50 has an angular abutment plate 4 projecting from its outer surface below the bar 2, and said member also has one end of a resilient strip 5 fastened thereto, said strip 5 being outwardly inclined and having its free end 55 portion bent at substantially right angles and projected toward the side member to

provide a rest 6 that is slidable in a transverse slot 7 formed in said member. Side member 1^a has one end of a supporting bar 8 hinged thereto, the other end of said bar 60 adapted to seat on rest 6 and beneath abutment plate 4, which retains bar 8 in spaced parallel relation to bar 2.

An ironing board 9 is provided on the under surface with hinges which are preferably of the type shown in Figs. 6 and 7. Said hinges are formed of a single sheet of metal bent to provide the oppositely disposed parallel ears 10 and the back plate 11 that is suitably fastened to the board 9. The 70 side members 1, 1^a are provided with similar hinges 12 and the brace bars 13 pivotally connect the hinges of said side members with the hinges of the board. One end of the board 9 is provided with a transverse groove 75 14 and said grooved end fits between bars 2 and 8, bar 2 engaging the groove 14.

As will be clear from the foregoing, the board 9 is supported in position for use by means of the engagement of the grooved 80 end thereof with the bars 2 and 8 and the brace bars 13. To fold the board, rest 6 is pressed into the slot of side member 1 so that bar 8 will be permitted to drop to a vertical position, whereupon the board may 85 be rocked to the position shown in Figs. 2 and 4 and by means of hooks 15 carried by members 1, 1^a and eyes 16 carried by the board, retained in an upright position parallel to the wall. To place the board in position for use, the hooks 15 are disengaged and the board allowed to drop until the groove 14 engages bar 2, whereupon bar 8 is swung up and snapped over resilient rest 6 and engages abutment 4, rest 6 springing to position beneath bar 8 to retain said bar in contact with the under surface of the board.

What I claim as my invention is:—

1. An ironing table comprising a frame provided with wall-engaging side members, 100 a bar connecting the upper ends thereof, a supporting bar pivotally connected to one side member, means carried by the other side member for normally retaining the supporting bar in spaced parallel relation to the 105 connecting bar, a board having a grooved end adapted to be fitted between the connecting bar and the supporting bar, and braces pivotally connecting the said board to the said side members.

2. An ironing table comprising a wall frame provided with a connecting bar, a

- supporting bar having one end pivotally connected to one portion of said frame, a resilient seat carried by said frame for normally supporting the free end of the supporting bar, braces pivotally connected to said frame, and a board pivotally connected to said braces and adapted to have one end seated on the supporting bar and engaged by the connecting bar.
- 10 3. An ironing table comprising a wall frame formed of side members and a connecting bar for the upper ends thereof, a supporting bar pivotally connected to one side member, an abutment plate carried by the other side member, a resilient seat also carried by said side member and adapted to normally retain the free end of the supporting bar in engagement with said abutment,
- a board adapted to have one end supported between said bars, and braces pivotally connecting said board to said side members. 20
4. An ironing table comprising a wall frame, a board pivotally connected thereto and provided with a transverse end groove in its upper surface, a bar carried by said frame for engaging said groove, and a second bar pivotally connected to said frame for engaging the under surface of said board to retain said board in engagement with the first-mentioned bar. 2

In testimony whereof I hereunto affix my signature in presence of two witnesses.

GEORGE L. BAXTER.
